COTTER KEY

John A. MacLean, Jr., Winnetka, Ill., and Benjamin Franklin Money, Tulsa, Okla., assignors to MacLean-Fogg Lock Nut Company, Chicago, Ill., a corporation of Illinois

Application May 21, 1945, Serial No. 595,024

2 Claims. (Cl. 85—8.5)

1

Our present invention relates to cotter keys and particularly to those of a type which, when installed in appropriate cotter receiving holes of parts with which they are adapted to cooperate, have a plurality of surfaces forcibly engaging and held against the wall of the hole, with the result that rattling of the cotter key and consequent wear of both the cotter key and the wall of the hole are prevented.

As a general object the present invention contemplates the provision of cotter key structure including a displaced section, deformable in use and having wedge-like and somewhat resilient characteristics adapted forcibly to hold the cotter key within a cotter receiving opening of an appropriate size.

In a cotter key having two normally adjacent legs, the invention provides for the sidewise curvature of adjacent intermediate portions of the legs without affecting the alignment of the other portions of the legs, the curvature and the position thereof being such that said cotter pin is forcibly retained within an opening of appropriate size in a co-acting cotter receiving part.

Another object of this invention is to provide an improved cotter key adapted to fit snugly in either a normal or oversize cotter receiving opening.

In addition to the displacement or curvature defined in the foregoing objects, our present invention comprehends the normal separation of the cotter key legs by an amount such that normal resilience of the legs aids in the holding action.

Other features, objects and advantages of our present invention will appear from the following detailed description wherein reference is made to the accompanying drawings.

Referring to the single sheet of drawings:

Figs. 1, 2 and 3 are respectively edge, side and end elevational views of one form of our improved cotter key as it appears before being placed in the cotter-receiving opening of a bolt, pin or other part with which it is adapted to co-act;

Fig. 4 is a sectional view showing the cotter key of Figs. 1, 2 and 3 as it appears after being driven into an appropriate cotter receiving hole of a co-acting part;

Figs. 5, 6 and 7 are respectively edge, side and end elevational views of a modified form of our cotter key as it appears before being inserted into the cotter receiving hole of a co-acting part;

Fig. 8 is a sectional view of the cotter key shown in Figs. 5, 6 and 7 as it appears after being installed in a cotter receiving hole of normal size in a co-acting part;

2

Fig. 9 is a sectional view similar to Fig. 8 which illustrates the cotter key of Figs. 5, 6 and 7 as it appears when appropriately installed in a cotter receiving opening that is over-size;

Fig. 10 is an edge elevational view, similar to Fig. 2, of another modified form of our cotter key as it appears before insertion into a cotter receiving opening; and

Figs. 11 and 12 are respectively sectional views 10 of the cotter key shown in Fig. 10 as it appears when inserted into normal and oversize cotter receiving openings.

Referring to the exemplary embodiment of our cotter key shown in Figs. 1, 2 and 3, it comprises 15 a piece of half round metal wire which has been return-bent and formed to define a head loop 10 with legs 12 and 13 extending therefrom. One leg, such as 13 in the illustrated embodiment, is desirably somewhat longer than the other to facilitate 20 the separation of the legs after the installation of the cotter key. The flat faces of the half round wire stock face one another and desirably extend in separated but closely spaced relation, diverging at one end toward the head loop. 25 The material used in the wire stock is preferably a steel such as that which has been found suitable for cotter keys and which possesses some resilience and the capability of deformation.

Although there are various ways in which the 30 finished cotter key might be manufactured, it is considered preferable that after the formation of the key with the rounded head loop 10 and integral projecting legs 12 and 13, diverging at 12a and 13a near one end and toward the head loop, 35 similar offset portions or protuberances 14 and 15 are formed in adjacent relation on one side of the legs by depression of the legs as at 16 and 17 from the opposite sides. It is the purpose of the protuberances to provide wedge-like offset portions on the sides of the legs having relatively smooth curvature with respect to the aligned end portions of the legs. The curved surfaces of the protuberances and opposite indentations are preferably of substantially arcuate contour and concentric with respect to a common axis.

Since the legs 12 and 13 of the cotter key diverge at 12a and 13a adjacent the head loop 10, that divergence provides outer surfaces on the cotter key which taper outwardly in one plane to 50 effect a tight fit between the key and the wall of one end of an appropriate cotter receiving opening when the cotter key is forced into the opening. The function of the protuberances 14 and 15, however, is not only to insure a tight fit of 55 the cotter key against the walls of the cotter re-

ceiving opening at positions spaced from the head loop, but also to separately effect tight engagement of both legs of the cotter key within the opening and in a direction transverse to that effected by the divergence of the legs. The protuberances are consequently spaced from the head loop although sufficiently close thereto to engage the wall of a cotter receiving opening 18 in a bolt or other desired part 19, as illustrated in Fig. 4. Thus, it may be understood that when the cotter key of Figs. 1-4 inclusive is inserted into an opening of appropriate size, the protuberances effect forced engagement of the key with the wall of the opening on opposite sides thereof and normally at substantially three points in one plane. The insertion to a position in which the diverging legs contact the wall of the opening adjacent the head loop adds additional and opposite points of engagement in a plane separate and transverse to the aforementioned plane.

For effective use, it is desirable that the cotter receiving opening 18 shall be of a size which freely receives the extending ends of the legs 12 and 13 but which will engage and somewhat deform the surfaces of the protuberances 14 and 15 to produce the desired wedging action which forces the opposite sides of the legs into tight engagement with the wall of the opening. The divergence of the legs 12 and 13 from one another and toward the head loop desirably starts at or near the offset portions of the legs and is of a magnitude such that the opposed outer surfaces of the legs 12 and 13 tightly engage the wall of an opening of a size appropriate for effecting the desired wedging action of the protuberances 14 and 15.

The modified form of our cotter key, which is illustrated in Figs. 5 to 9 inclusive, includes elements similar to those illustrated and described in connection with the form shown in Figs. 1 to 4 inclusive, which elements are designated by like reference numerals.

Although the cotter key shown in Figs. 5 to 9 inclusive includes the elements such as the head loop 18 and extending legs 12 and 13, as well as the offset portion intermediate the aligned ends of the legs which provides the protuberances 14 and 15, it is characterized by leg portions 12b and 13b adjacent the head loop which, although desirably diverging outwardly toward the head loop, are more widely separated than the diverging portions 12a and 13a of the form shown in Figs. 1 to 4 inclusive. The wider separation of the portions 12b and 13b of the cotter key legs of the form shown in Figs. 5 to 9 inclusive is effected by relatively abrupt angular deformation of the legs 12 and 13 at 12c and 13c.

Upon being installed in a cotter receiving bore 18 of normal size, the wedging action of the protuberances 14 and 15 is similar to that described with respect to the form shown in Figs. 1 to 4 inclusive, but the portions 12c and 13c of the legs provide stops limiting the movement of the cotter key into the bore. The installation of the cotter key in an opening of normal size is illustrated in Fig. 8, wherein the protuberances 14 and 15 effect tight engagement of the cotter key legs within the bore 18 while the portions 12c and 13c abut the end walls of the bore. The points of engagement between the cotter key and the wall of an opening of proper size, or only slightly oversize, are similar to those described with reference to Figs. 1-4 inclusive. That is, the forced engagement effected by the presence of the protuberance is normally in one plane; while the addi-

tional contact resulting from full and proper insertion of the key into the opening and against the diverging portions 12c and 13c is in a transverse plane.

As illustrated in Fig. 9, the cotter key of the form shown in Figs. 5 to 9 inclusive is adapted to service in instances where a bore 18a in part 19a has become over-size due to wear or some other reason. In such instances, this form of cotter key is driven into the opening to an extent such that the more widely separated portions 12b and 13b of the legs 12 and 13 are forced into the opening. The resulting forced fit of the portions 12b and 13b of the legs of the cotter key within the opening 18a will serve firmly to hold the cotter key against movement or rattling within the opening.

Like the previously described modified form, the modification of our invention which is illustrated in Figs. 10, 11 and 12 also includes parts bearing reference numerals like those previously referred to which function similarly.

In addition to the parts such as the head loop 18, extending legs 12 and 13 and the protuberances such as 15 opposite depressions 16 and 17 for firmly holding the cotter key in an opening 18 of normal size, the cotter key shown in Figs. 10, 11 and 12 is additionally provided with a second deformed portion of larger size adapted to hold the cotter key in an oversize opening. Longitudinally spaced along the legs 12 and 13 from the protuberances 14 and 15, and disposed between the latter protuberances and the head loop 18 are protuberances such as 15a which extend laterally beyond the protuberances 14 and 15. The larger protuberances such as 15a are formed in a manner similar to the protuberances 14 and 15 with opposite depressions 16a and 17a and project in the same direction from the legs.

In an opening of appropriate size, the smaller protuberances function in the manner of the previously described protuberances; although the larger protuberance provides a stop for insertion of the key and an additional point of contact with the wall of the opening in substantially the same plane as the contacting points of the smaller protuberances.

As shown in Fig. 11, the cotter key, when installed in an opening 18 of normal size, is snugly held in the opening by the protuberances 14 and 15, while the larger protuberances act as stops to limit the movement of the cotter key into the opening. However, when the cotter receiving opening is oversize or worn as indicated at 18b in Fig. 12, the normal sized protuberances 14 and 15 pass through the opening and the larger ones serve to effect the snug fit of the cotter key within the opening. In the latter instance the head ring limits the movement of the cotter key into the opening as it does in the form shown in Figs. 1, 2 and 3.

In all of the forms of the cotter key disclosed, of course, endwise movement of the cotter keys from the opening is prevented by bending the ends of the legs outwardly, as indicated in Fig. 9. It may also be understood with respect to all of the forms that the protuberances are desirably of a size which produces a snug fit in openings of reasonable oversize and are deformed upon insertion to fit smaller openings.

The steps by which the cotter keys of Figs. 5 to 7 inclusive and 10 are manufactured may be similar to those for the production of the form shown in Figs. 1 to 3 inclusive, and the side-wise deformation of the legs to produce either one or

two sets of the protuberances may be done after the formation of the rest of the key.

While we have illustrated and described a preferred embodiment of our invention, many modifications may be made without departing from the spirit of the invention, and we do not wish to be limited to the precise details set forth, but desire to avail ourselves of all changes within the scope of the appended claims.

Having thus described our invention, what we claim as new and desire to secure by Letters Patent of the United States is:

1. A cotter key adapted to fit snugly into an appropriate cotter-receiving aperture and comprising a pair of legs of substantially semi-circular section extending in adjacent and closely spaced relationship from an integral head loop, said legs having plane surfaces facing one another, the major portions of the length of each of said legs being substantially straight and aligned as viewed in a direction perpendicular to said plane surfaces, and adjacent intermediate portions of each of said legs being similarly bent to one side in a direction crosswise of said plane surfaces to form smoothly curved offset portions adapted to serve as wedges in said cotter-receiving aperture to effect tight engagement of the key in the aperture in directions at right angles to each other.

2. A cotter key adapted to fit snugly in either a normal or worn cotter-receiving opening and

comprising, in combination, a length of semi-circular wire return bent to provide a head loop at one end and a pair of extending legs disposed with their flat surfaces in face to face relationship, adjacent portions of the legs intermediate their ends being similarly bent sidewise of the legs in the plane of the flat surfaces at longitudinally separated positions to provide two sets of similarly shaped offset protuberances displaced from each other along the same sides of the legs, the set of said protuberances nearer the head loop projecting laterally beyond the other set so as to act as a stop for endwise movement of the legs into a cotter-receiving opening of normal size wherein said other set fits snugly, and said set of protuberances nearer the head loop fitting snugly into a worn cotter-receiving opening.
